D. H. YOUNG

BROOM

Filed Oct. 7, 1921

Fig. 1.

UNITED STATES PATENT OFFICE.

DANIEL H. YOUNG, OF MANCHESTER, IOWA.

BROOM.

Application filed October 7, 1921. Serial No. 506,137.

To all whom it may concern:

Be it known that I, DANIEL H. YOUNG, a citizen of the United States of America, and a resident of Manchester, Delaware County, 5 Iowa, have invented certain new and useful Improvements in Brooms, of which the following is a specification.

My invention relates to improvements in brooms, and the object of my improvement 10 is to provide a broom suitable for sweeping lawns or other surfaces, adapted to both gather and deliver efficiently and quickly, the appliance being light and inexpensive for manual handling.

15 This object I have accomplished by the means which are hereinafter described and claimed, and which are illustrated in the accompanying drawings, in which Fig. 1 is a rear elevation of my improved device, and 20 Fig. 2 is a fragmental end elevation of the head and broom parts on a larger scale, with parts broken away. Fig. 3 is a fragmental rear elevation of a modification thereof. Fig. 25 4 is a front elevation of another modification of the device, and Fig. 5 is a fragmental end elevation of the head and broom parts of the device shown in said Fig. 4.

Similar numerals of reference denote corresponding parts throughout the several 30 views.

My improved implement is of the class of brooms constructed specifically for raking over surfaces such as plots of grass or leaf covered places, in which situations it is desirable that the raking or brushing means should have spaced gathering teeth or projections of a rake-like description, yet retaining in these teeth or projections the length and elastic flexibility of a broom.

40 Referring first to Figs. 1 and 2, the numeral 4 denotes an elongated handle, on one end of which is fixedly mounted a cross-piece or head to carry the broom wires 7. This head may be constructed of two like elongated parts 1 and 2 placed in registering contact and secured together by means of any suitable fastenings, such as the screws 18. To strengthen and more rigidly connect said head and the handle 4, both have registering 45 sockets to receive a short metallic cylinder 5. This cylinder prevents relative displacements of said parts under the stresses of use.

The broom consists of any desired number of light elastic wire teeth 7 preferably 50 convex toward the location of application, and having their free ends bent in the same

direction at 8 at a slight angle. This convexity of the teeth lends flexibility in the direction mentioned and makes them somewhat more rigid in a direction longitudinal 60 with the broom head. The other ends of said teeth may be fixedly removably secured to said head interlockingly in any desired manner, but as shown, these ends are passed between the head parts 1 and 2 and 65 have their extremities bent at a right angle at 9, the ends 9 being driven into either part 1 or 2 or seated in sockets provided at 4 before the parts 1 and 2 are secured together. 70

As shown in Fig. 2, one inner longitudinal angle of the rear part 1 may be beveled at 3 opposite the bent parts 9 of the teeth to afford rear clearance space, permitting the teeth 7 to flex rearwardly under the stresses of use against the beveled surface without 75 danger of bending at that place as might be the case with the teeth held tightly against a rectangular corner, for it is well known that constant slight bendings of such metal parts eventually cause crystallization at the 80 place frequently bent, resulting in breakage.

Metal gussets 12 may be secured by means of screws 6 on opposite sides of the junction of and to said head 1-2 and handle 4 to give great rigidity thereto. 85

Means may be provided for affording medial support to said teeth 7, which may be an elastic cross-rod 13 positioned medially across and in contact with the convex sides of said teeth 7, the rod being bent at the 90 places 11 around the end teeth and then preferably directed convergingly across the convex sides of said teeth toward and across the head-part 1 to which its extremities are secured by means of staples 14. It will be seen 95 that the parts 10 of the rod approach said head at less than a right angle which permits these parts to be bent to and fro to space the cross part 13 at desired adjusted distances from said head to secure proper support to the teeth under different conditions of use. The angular shoulders at 11 also limit or restrict the outward spreading of said teeth. 100

The modification shown in Fig. 3 displays 105 a medially bent cross-rod 15-17 for one or a pair of teeth 7 whose shoulders 16 are recurved to limit spreading of the teeth apart, the extremities of the rod being secured to the head 1.

In the modification shown in Figs. 4 and 5, the head is composed of a single part 2 110

between like parts 1 forming joints there-with for the reception of spaced apart stag-
gered teeth 7 and 19 whose ends 9 are bent
and secured to the head in the manner here-
5 inbefore described. These teeth may be
straight as shown, or may be curved as in
Fig. 2. In this case, the cross-rod 13 is pref-
erably interwoven with both sets of teeth 7
and 19 to thereby support both sets medially,
10 the shoulders 11 serving the same purpose
of limiting the spread of the terminal teeth
7 while the parts 10 are directed toward and
secured to opposite ends of said head.

The broom teeth may be made of elastic
15 steel, brass or other material, while the de-
tails of construction of the appliance may be
varied without departing from this inven-
tion.

In use, this device is manipulated like a
20 broom rather than a rake, and its relatively
long elastic teeth thus have a penetrative and
gathering effect not possible to the short
rigid teeth of a rake, while the smallness,
elasticity and length of the teeth afford quick
25 and easy clearance of the load when the in-
strument is lifted. The teeth cannot become
clogged.

Having described my invention, what I
claim as new and desire to secure by Letters
30 Patent, is:

1. A device of the character described,

comprising a head, a broom mounted there-
on composed of elastic wires, and an adjust-
able elastic device crossing said wires inter-
lacingly to support them medially, said de-
vice being bent slopingly near each end to
ward and secured at its extremities to said
head, the sloping parts of the device being
deformable to adjust the position of the de-
vice along the broom-wires. 35

2. In combination, a head-block, spaced
elastic broom-wires mounted thereon, and a
bendable element interlaced around the mid-
dle parts of said broom-wires with its ex-
tremities positioned relatively near the mid-
dle of the head-block and secured thereto. 40

3. A device of the character described,
comprising a head element, and elastic elong-
ated teeth arranged therealong at varying
angles thereto, means for securing said teeth 50
to said head element removably, and a bend-
able reinforcing element crossing said teeth,
bent around the end teeth, directed slopingly
toward and then terminally fastened to said
head element, said reinforcing element adapt-
ed to have its crossing part adjusted along
said teeth by varying the angle of the slop-
ing parts with respect to that part which
crosses the teeth. 55

Signed at Waterloo, Iowa, this 1st day of 60
October, 1921.

DANIEL H. YOUNG.
